FIG. 1 is a front elevation view of a telephone set showing my new design as a wall mounted set;

FIG. 2 is a left side elevation view of the wall mounted set of FIG. 1;

FIG. 3 is a right side elevation view of the wall mounted set of FIG. 1;

FIG. 4 is a top plan view of the wall mounted set of FIG. 1;

FIG. 5 is an isometric view of the telephone set shown in FIG. 1 showing and illustrating my new design as a table or desk top set;

FIG. 6 is a front elevation view of a second modified embodiment of a telephone set showing my new design as a wall mounted set;

FIG. 7 is a left side elevation view of the wall mounted set of FIG. 6;

FIG. 8 is a right side elevation view of the wall mounted set of FIG. 6;

FIG. 9 is a top plan view of the wall mounted set of FIG. 6;

FIG. 10 is an isometric view of the second modified embodiment of FIG. 6 showing the telephone set as a table or desk top set;

FIG. 11 is a front elevation view of a third modified embodiment of a telephone set showing my new design as a wall mounted set;

FIG. 12 is a left side elevation view of the wall mounted set of FIG. 11;

FIG. 13 is a right side elevation view of the wall mounted set of FIG. 11;

FIG. 14 is a top plan view of the wall mounted set of FIG. 11;

FIG. 15 is an isometric view of the third modified embodiment of FIG. 11 showing the telephone set as a table or desk top set;

FIG. 16 is a front elevation view of a fourth modified embodiment of a telephone set showing my new design as a wall mounted set;

FIG. 17 is a left side elevation view of the wall mounted set of FIG. 16;

FIG. 18 is a right side elevation view of the wall mounted set of FIG. 16;

FIG. 19 is a top plan view of the wall mounted set of FIG. 16; and

FIG. 20 is an isometric view of the fourth modified embodiment of FIG. 16 showing the telephone set as a table or desk top set.

This is a continuation-in-part of design application Serial Nos. D. 380,278, D. 380,465, D. 380,466, D. 380,490, filed July 18, 1973, all now abandoned.

I claim:

The ornamental design for a telephone set, substantially as shown and described.
